ADJUSTABLE STRIKE PLATE

Fred J. Russell, Los Angeles, Calif.

Application April 1, 1955, Serial No. 498,727

3 Claims. (Cl. 292—341.18)

The invention relates to door hardware and has particular reference to a strike plate so constructed that it can be adjusted to vary the size of the opening in the strike plate which is adapted to receive the latch bolt.

Strike plates have been so constantly in use for a great many years that their general form and configuration has commonly been accepted as conventionalized. They are regularly made of sheet material stamped to a rather simple acceptable form and apertured to receive the latch bolt when the door is closed. Usual forms of strike plate have one or two holes frequently rectangular, the holes being made to fit the latch bolt. The adjustment is usually made on the door frame when the strike plate is installed. Some adjustment is usually necessary so that the latch bolt will fit neatly into the strike plate and hold the door firmly in closed position without such freedom as will allow undesirable rattling. Limitations ordinarily present in conditioning the wooden frame for reception of the strike plate render it likely that relatively few strike plates will be positioned to best advantage on the door frame without careful and expert attention. Should a mistake be made in the locating of the strike plate, the mistakes are usually a matter of fractions of an inch and it becomes extremely difficult to reset the screws the necessary small fraction of an inch from the original screw holes without leaving undesirable looseness in the screw setting which may ultimately permit the strike plate to be dislodged and misaligned.

It is therefore among the objects of the invention to provide a new and improved adjustable strike plate wherein the aperture which is adapted to receive the latch bolt can be varied as to its breadth in order to properly accommodate the latch bolt.

Another object of the invention is to provide a new and improved adjustable strike plate which permits adjustment of the deflecting side of the latch bolt without it being necessary to reset the screws which are designed to hold the strike plate on the door frame.

Still another object of the invention is to provide a new and improved adjustable strike plate which permits of very easy adjustment of the side of the strike plate designed to engage the latch bolt after the screws which hold the strike plate in position have been partially set.

Still further among the objects of the invention is to provide a new and improved adjustable strike plate which is simple in its design though composed of two parts, the parts being so constructed that they can be set in a great number of different positions of adjustment by being shifted only slightly with respect to each other and thereafter firmly anchored in the selected position of adjustment without likelihood of dislodgment under virtually any and all conditions of operation.

With these and other objects in view, the invention consists in the construction, arrangement and combination of the various parts of the device whereby the objects contemplated are attained, as hereinafter set forth, pointed out in the appended claims and illustrated in the accompanying drawings.

2

In the drawings:

Figure 1 is a side elevational view of the edge of a door with a strike plate installed.

Figure 2 is a longitudinal sectional view taken on the line 2—2 of Figure 1.

Figure 3 is a longitudinal sectional view taken on the line 3—3 of Figure 2.

Figure 4 is an exploded view of the two portions of the adjustable strike plate of Figure 1.

Figure 5 is a fragmentary longitudinal sectional view of a modified form of the device.

Figure 6 is a fragmentary exploded view of the modified form of the device shown in Figure 5.

Figure 7 is an elevational view of a second modified form of the invention showing the strike plate attached to a door frame.

Figure 8 is a longitudinal sectional view taken on the line 8—8 of Figure 7.

Figure 9 is a cross-sectional view taken on the line 9—9 of Figure 7.

In the form of the invention chosen for the purpose of illustration there is pictured a conventional door frame 10 having an edge 11 exposed to view. A latch bolt recess 12 extends inwardly from the edge of the frame and surrounding the latch bolt recess is a mortised area 13 of such depth as to normally permit a strike plate, indicated generally by the reference character 14, to be set therein and finished flush with the edge of the frame.

The strike plate herein described comprises two separate members adapted to cooperate one with another. A deflecting member 15 is located on one side and lies beneath a containing member 16. More particularly the deflecting member consists of a pair of upper and lower arms 17 and 18, respectively, which are joined at one end of each by a deflecting element 19. Thus constructed the arms and the deflecting element encompass a laterally open aperture 20. The deflecting member is further provided with a deflecting lip 21, ordinarily turned over in an arc so as to receive the impact of the bevelled face of a conventional latch bolt.

Each arm is provided with a longitudinally extending slot 22 of sufficient breadth to easily accommodate one of the screws 23.

Moreover, on the outside edges 24 of the arms 17 and 18 are a series of serrations, inside edges 25 being provided with similar serrations.

The restraining member 16 also includes a pair of spaced upper and lower legs 26 and 27, respectively. These legs are similar in breadth and length to the legs 17 and 18 of the deflecting member and are adapted to underlie the legs 17 and 18. A restraining element 28 connects ends of the legs 26 and 27 and assists in forming a laterally open recess 29. The recess 29 as to its upper and lower edges is adapted to coincide with the corresponding upper and lower edges of the recess 20.

On each outside edge of the respective arms 26 and 27 is a straight flange 30 provided on its inside face with serrations 31. A shorter straight flange 32 forms part of each inside edge 33 of each of the legs 26 and 27. Each 60 of the legs has a screw hole 34 and around the edge of each of the screw holes is a bevelled portion 35 adapted on the concave side to receive the head of the respective screw 23 in countersunk position and adapted to extend outwardly on the opposite side into the respective slot 22. Engagement of the bevelled portion 35 in the slot in each case assists in maintaining a snug contact between them when the parts of the strike plate are installed on a door frame.

When the strike plate is to be installed on a door frame, the deflecting member is placed with fixed legs 17 and 18 between the legs 26 and 27, respectively, of the restraining member. No special adjustment need be made

initially while the members together are applied to the largest area 13 and the screws 23 started into the frame. It is necessary at this point only to have the screws in reasonably neat alignment in a vertical direction.

Once this initial step has been accomplished, the deflecting member can be pressed against the bottom of the mortised recess and the restraining member held up against the heads of the screws to a position where the serrations are out of engagement. The deflecting member can then be moved in or out so as to enlarge or diminish the breadth of the space formed by the laterally opened recesses. When the proper position has been reached within the limit permitted by the size of the serrations, the deflecting member is held in the selected position and the restraining member pushed against it so as to engage recesses on the respective sides of the arms. The slots 22 permit the desired movement. Once in position the screws 23 are driven snugly into the frame and the adjustable strike plate has been permanently set. Should readjustment be necessary, the screws 23 can be partly withdrawn, the restraining member lifted outwardly, and the striking member reset to a preferred new position of adjustment, after which the screws are again driven into the frame. Engagement of the serrations prevents movement of the strike member relative to the restraining member regardless of the character of impact against the lip of the strike member or movement in the opposite direction of a latch bolt against the deflecting member.

To improve a neatness of appearance the legs 17 and 18 may be bent slightly inwardly and the deflecting element 19 bent slightly outwardly in order that the exposed surface of the element 19 be flush with the visible faces of the legs 26 and 27 when the strike plate is in position on a door frame.

In a modified form of the invention illustrated in Figures 5 and 6 legs 40 of a restraining member 41 have smooth outer edges and on inner edges 42 are provided with bent flanges comprising a horizontal leg 43 and a vertical leg 44. The leg 43 is of such depth that the vertical leg 44 is spaced a distance from the arm 40 to provide a space in excess of double the thickness of an arm 45 of a deflecting member 46. It will be noted that an inside edge 47 of each arm 45 has serrations whereas an outside edge 48 is smooth. The outside edge corresponds approximately with an outside edge 49 of each of the legs 40.

On the inside face of the horizontal leg 43 there is provided a row of serrations 50 having a breadth substantially equal to the thickness of the arm 45. A clear recess 51 makes up the remainder of the inside face of the leg 43.

Accordingly when the modified form of the device is to be mounted on a door frame, the screws 23 are started as previously described with the restraining member 41 in its proper position. Screw holes 52 in the restraining member match slots 53 in the deflecting member 46. With the screws 23 only partly driven, the striking member can be held outwardly against the heads of the screws in which position the vertical legs 44 of the bent flange move into engagement with the arms 45 at which point the serrations are out of engagement, the serrations 47 of the legs 45 being at that time within the clear recesses 51. This relative arrangement of parts permits the deflecting member to be moved in or out to a desired position of adjustment after which the restraining member is pushed against the deflecting member and against the door frame and the screws 23 driven into the frame. Because of the fact that the legs 44 fall within the latch bolt recess 12, pressure of the heads of the screws 23 against the restraining member legs 40 force the legs into engagement with the corresponding legs 45 of the deflecting member and both parts are anchored together and to the door frame. Any necessary readjustment can be made as described in connection with the form of the invention initially referred to.

In the modified form of the device the overlying character of the vertical legs 44 serve to hold the separate members of the adjustable strike plate together so that they can be more easily handled as a unit especially in those instances where one or another of the screws 23 are inserted through the appropriate openings designed to receive them.

Either form of the invention is equal in its effectiveness in that it can be easily applied in a semi-adjusted position 10 to the door frame with screws started in the positions which they will ultimately occupy. Adjustment can then be made in that side of the strike plate which is the critical side, namely, the side which is engaged by the latch bolt in the opening and shutting of the door and the parts anchored permanently with respect to each other and the door frame after the proper position of adjustment has been determined.

In the form of the invention illustrated in Figure 8 a deflecting member indicated generally by the reference 20 character 60 is provided as previously suggested with a deflecting element 61 connected between arms 62 and 63. At the outer end of the deflecting element is a smoothly curved lip 64, the curvature of which is capable of receiving the impact of the latch bolt and to smoothly slide the 25 latch bolt into the latch as the door is closed. It will be noted that at the base of the lip the deflecting element is offset with respect to the surface of the deflecting member so that an inner rounded edge 65 is flush with the outer surface of the containing member 16.

30 A flat portion 66 at the base of the deflecting element extends in a direction perpendicular to the surfaces of the faces of the adjustable members and extends a distance equal to several times the thickness of the members in a direction such that it would normally enter the latch bolt recess 12. The flat portion 66 is especially advantageous in an adjustable strike plate of the kind herein described where a recess 67 is chiseled relatively deeply into the edge of the door frame without there being left any portion of the wood for resisting a shifting of the strike plate. Inasmuch as a clear recess 67 is desirable to permit free adjustment of the deflecting member, it becomes advantageous to be able to locate the deflecting member approximately before the screws are driven to the location of Figure 9, preferably leaving a slight clearance between the flat portion 66 and a wall 68 of the latch bolt recess. The slight clearance will permit of some adjustment of the deflecting member outwardly as well as it being possible to adjust the deflecting member inwardly. After the screws have been driven and the strike plate set, should there be an occasion where exceptional strain is put upon the strike plate forcing it toward the left, as viewed in Figure 7, the flat portion 66 will then fall into position against the wall 68 of the latch bolt recess and prevent the strike plate from being torn loose.

55 The device is simple in its construction which facilitates inexpensive manufacture and rugged by reason of portions being bent at angles suitable for reinforcement while also serving to adapt the plate to its use. Because of its versatility only one size will be adapted to accommodate many different circumstances by reason of the fact that the final adjustment can be made after the strike plate has been applied to the millwork where it is to be ultimately used.

60 While I have herein shown and described my invention in what I have conceived to be the most practical and preferred embodiment, it is recognized that departures may be made therefrom within the scope of my invention, which is not to be limited to the details disclosed herein but is to be accorded the full scope of the claims so as to embrace any and all equivalent devices.

65 Having described my invention, what I claim as new and desire to secure by Letters Patent is:

1. An adjustable strike plate for installation in a door frame wherein a latch bolt recess has been formed, said

strike plate comprising a bolt deflecting member and a containing member, said bolt deflecting member including spaced arms adapted to extend transversely of the edge of the door and a strike lip element extending between ends of said arms to form a laterally open aperture adapted to overlie the bolt recess, said lip being deflected from the plane of the arms and said arms having longitudinally extending screw receiving slots therein, said containing member including arms in overlapped relation with the first identified arms and a containing element extending between ends of said containing member to form a laterally open aperture adapted to overlie the bolt recess, serrations on oppositely positioned edges of the arms of one said member which underlie the other arms when installed, said serrations extending in a direction perpendicular to the surfaces of said one member, flanges on the arms which are in overlying position when installed, said flanges being of thickness not greater than the thickness of the arms in underlying position and facing the serrated edges of the arms in underlying position and serrations on said flanges adapted to engage said serrations on the arms in underlying position at selected positions of one set of arms upon the other whereby to vary the location of a latch retaining edge of a common recess between elements connecting said arms, the arms of said containing member having countersunk depressions insertable in said slots and in engagement with the edges thereof, and means forming screw receiving holes in said depressions adapted for alignment with said slots at different positions of adjustment.

2. An adjustable strike plate for installation in a door frame comprising a bolt deflecting member and a containing member, said bolt deflecting member including spaced arms having opposite smooth surfaces adapted to extend transversely of the edge of the door and a strike lip element extending between ends of said arms to form one side of a strike bolt aperture, and serrations on edges of said arms, said containing member including arms having opposite smooth surfaces and adapted to overlie the first identified arms and a containing element extending between ends of said containing member to form another side of said strike bolt aperture, said last identified arms each having on the inside edge a bent flange, one leg of said flange having an inner portion thereof including serrations of length comparable to the thickness of the arms of the deflecting member and

adapted to engage serrations of the adjacent edge of the corresponding arm of the deflecting member and an unserrated recessed portion adapted to clear said last identified serrations, another leg of said flange at the free end of said first leg having a position overlying the face of said corresponding arm whereby to prevent complete separation of said members during adjustment, the arms of one of said members having slots therein and the arms of the other member having screw receiving holes adapted for adjustable alignment with said slots.

3. An adjustable strike plate for installation in a door frame comprising a bolt deflecting member and a containing member, said bolt deflecting member including spaced arms and a strike-lip element extending between ends of said arms to form a latch bolt aperture, serrations on opposite edges of said arms, said containing member including arms adapted to overlie the first identified arms and a containing element extending between ends of said containing member to form a latch bolt aperture, said arms on one of said members having flanges of depth substantially equal to the thickness of the arms of the other member and overlying edges of said arms on the other member, serrations respectively on the flanges and the edges extending normal to the faces of the members adapted to engage at selected positions of one set of arms upon the other, whereby to vary the location of a latch bolt retaining edge of a common aperture between elements connecting said arms, said bolt deflecting member having a flat portion at the base of the strike lip element turned toward the under side of the lip to a position adapted to engage a portion of the door frame when the strike plate is in a position of relatively wide adjustment, the arms of one of said members having slots and the corresponding arms of the other member having screw receiving holes adapted for alignment with said slots at different positions of adjustment.
